F. D. HOFFMAN

SMOKE CONSUMER

Filed Oct. 10, 1925

UNITED STATES PATENT OFFICE.

FRED D. HOFFMAN, OF KANSAS CITY, MISSOURI, ASSIGNOR TO HOFFMAN SMOKE ABATOR COMPANY, OF JACKSON COUNTY, MISSOURI, A COMMON-LAW TRUST.

SMOKE CONSUMER.

Application filed October 10, 1925. Serial No. 61,765.

My invention relates to smoke consumers, and more particularly to apparatus of that character for interrupting flow of unburned carbonaceous particles from a furnace to its stack and returning said particles to the furnace for combustion therein, the principal object of the present invention being to effectively collect the carbonaceous particles before they reach the stack and return them to the furnace for consumption.

In accomplishing this object I have provided improved details of structure, the preferred forms of which are illustrated in the accompanying drawings wherein:—

Fig. 1 is a perspective view of a furnace and its stack equipped with a smoke consumer embodying my improvements.

Fig. 2 is a vertical section on the line 2—2, Fig. 1.

Fig. 3 is a detail perspective view of the return spreader plate.

Referring more in detail to the drawings,

1 designates a furnace of any ordinary type, and 2 a stack of usual construction. Located between the furnace and its stack is a battery of housings 3, each substantially a duplicate of the other and comprising a box-like structure open at its front and provided with a door 4 hinged to the housing and preferably adapted for closure by bolts 5 projectable through apertures 6 in the door 4 and for receiving wing nuts 7.

Integral with the rear wall of the housing is a partition 8 which extends forwardly to the line of the front of the housing to divide the housing into separate vertical chambers, the upper end of the partition being inclined rearwardly to form an enlarged chamber 9 at the front upper corner of the housing, and the lower end of the partition being curved rearwardly and spaced from the rear edge wall of the housing to provide for easy flow from the front chamber to the rear one at the bottom of the housing. Formed integrally with the partition and extending downwardly at an incline from the opposite faces thereof are forwardly directed baffle ears 10 and rearwardly directed baffle ears 11, the rearwardly directed ears being of greater number and more closely spaced than those at the front of the partition.

Formed integrally with the edge walls of the housing and projecting at an incline therefrom in staggered relation with the baffles 10 and 11 are baffles 12 and 13 forming

tortuous paths through the separate flow chambers. Opening to the chamber 9 of the first housing in the battery is the flue 14 from the furnace 1, and opening from the top of the rear chamber of the housing is an outlet port 14', the port 14' of the housing first in the battery leading through a connection 15 to the intake port in the chamber 9 of the housing next in train, the port 14' of the last housing in train opening to an exhaust fan indicated by the housing 17 operable by a motor 18 and communicating through a conduit 19 with the stack 2.

Located adjacent the tops of the housings is a water supply pipe 20 having branches 22, each leading through the top of a housing to the chamber 9 thereof, and there provided with a downwardly directed nozzle 23 through which water may be sprayed into the primary baffle chamber. Located adjacent each of the housings, and connected with the water supply pipe 20 is a branch 24 that extends throughout the length of the housing and has offtakes 25 extending through the back wall of the housing and provided with nozzles 26 which discharge horizontally between the baffles 11 in said rear housing chamber. Leading from the bottom of each of the housings is a pipe 27 connecting with a manifold 28 leading back to the furnace and terminating therein in a spreader plate 29. The manifold 28 is provided with a drain pipe 30 through which contents of the housing may be drawn off to waste without delivery to the furnace, if desired. The manifold 28 has a valve 31 between the first housing and the furnace, and the drain pipe 30, a valve 32, whereby flow from the manifold may be directed to the furnace or to waste as desired.

The battery of housings is preferably connected by a tie rod 33 and the housings are spaced by lugs 34 preferably cast integrally with the front and rear edge walls of the housings.

Assuming the parts to be constructed and assembled as described, and the furnace in operation, the valve 31 in the manifold 28 is opened and the valve 32 in the drain pipe 30 closed to communicate the manifold with the furnace.

Non-combustible gases and unconsumed carbonaceous particles of the fuel forming in the furnace are carried through the flue 14 and delivered into the upper chamber 9

of the forward baffle chamber of the first housing in the battery, down which they are conducted to pass about the lower curved end of the partition and rise through the 5 rear baffle chamber for exit through the port 14', the flow being assisted by a spray from the nozzle in the upper portion of the chamber 9 which is constantly open to promote the flow, dampen the carbonaceous particles 10 and collect the particles in the bottom of the housing, draft through the flue and housings to the stack being promoted by the exhaust fan heretofore mentioned.

Carbonaceous particles not precipitated 15 by the spray in the primary baffle chamber pass into the secondary chamber and are carried about the baffles, where they encounter sprays from the horizontal nozzles and are collected and passed back to the bottom 20 of the housing in rich solution, which, with the particles precipitated by the first spray, passes out through the drain pipe to the manifold and is conducted back to the furnace. When the solution reaches the hot 25 spreader in the furnace the liquid content of the solution is vaporized, an explosive effect resulting from generation of the steam tending to distribute the carbonaceous particles so that they are spread into 30 the fire and consumed. Carbonaceous particles not collected in the first housing pass on to the second one, where the operation described in connection with the first housing is repeated, and all remaining carbons 35 returned to the furnace, so that by the time the fan is reached, the flow consists only of non-combustible gases.

After the furnace has been in operation 40 for some time, a considerable amount of carbonaceous matter will have collected on the baffles and walls of the respective housings. The valve 31 in the manifold is then closed, the valve 32 in the drain pipe 30 opened and the valves of the spray nozzles 45 opened wide to permit strong flushing sprays to be delivered through all of the nozzles which will dislodge the collected material from the walls and baffles and carry it off to waste. After the cleaning operation the 50 valves may be readjusted and the normal operation resumed.

With an apparatus such as described and operated as above set forth, the carbonaceous matter passing off from the furnace 55 as a result of incomplete combustion therein, is collected in the housings, so that it cannot escape through the stack as smoke, and is conducted back to the furnace to be burned, thereby effecting complete combustion of fuel.

What I claim and desire to secure by Letters-Patent is:—

1. In combination with a furnace and its stack, a housing comprising a partition dividing 65 the housing into separate vertical

passageways having communication with the bottom of the housing, baffles in said passageways in staggered relation to form a tortuous path for flow therethrough, means communicating the furnace with the upper 70 portion of the first passageway, and a nozzle for directing spray downwardly only in the passageway adjacent the intake from the furnace, and nozzles directed horizontally between the baffles in the rear passageway. 75

2. In combination with a furnace and its stack, a housing having its interior divided longitudinally to form forward and rear passageways, the partition terminating short of the bottom of the housing communicating the passageways and curved rearwardly to direct the flow to the rear passageway, means of communication between the furnace and the upper portion of the forward passageway, baffles in said passageways arranged in staggered relation to form a tortuous path, a nozzle directed downwardly in the top of the forward passageway, nozzles directed horizontally between the baffles in the rear passageway, and means for draining contents of the housing back to the furnace. 85

3. In combination with a furnace and its stack, a housing having its interior divided into forward and rearward passageways 95 communicating at the bottom of the housing, baffles inclined downwardly from opposite sides of the passageway in staggered relation to form a tortuous path, the housing having an intake port at the upper end of the forward passageway and an outlet port at the upper end of the rear passageway, a flue connecting the furnace with the intake port, an exhaust fan communicating with the outlet port and with the stack, a nozzle directed downwardly in the top of the forward passageway, nozzles directed horizontally between the baffles of the rear passageway, valved means for supplying fluid to the nozzles, a drain pipe opening to the bottom of the housing and leading to the interior of the furnace, and a spreader on the outlet end of the pipe. 100

4. In combination with a furnace and its stack, a battery of spaced housings, each having its interior divided longitudinally into separate passageways, each of the housings having an intake port at the upper end of its forward passageway and an outlet port at the rear edge of its rear passageway, means of communication between the outlet port of a forward housing and the intake port of a rear housing, a flue connecting the furnace with the intake port of the first housing in train, an exhaust fan communicating with the outlet port of the rear housing in train, the edge walls and partitions in each of the housings being provided with staggered baffles forming a tortuous path within the housing, a nozzle directed down- 115 120 125 130

wardly into the upper portion of each of the housings adjacent the intake port, horizontal nozzles arranged for discharging between the baffles in the rear passageway of each housing, drain pipes leading from the bottom of the housings, a manifold connected with the drain pipes and leading to the interior of the furnace, a spreader plate

on the outlet end of the manifold, a drain pipe leading from the manifold, and means 10 for selectively directing flow from the manifold to the furnace or to the drain pipe.

In testimony whereof I affix my signature.

FRED D. HOFFMAN.
